AIR CIRCULATOR

Samuel N. North, North Beach, Md.

Application September 22, 1942, Serial No. 459,308

8 Claims. (Cl. 230—250)

This invention relates to air circulators and more particularly to a portable fan especially designed for use in dwellings, office buildings and other places.

The object of the invention is to provide a fan of simple and inexpensive construction capable of being readily transported from place to place and which will circulate a greater volume of air at less expenditure of motor energy than heretofore.

A further object of the invention is to provide a fan having a deflecting cone secured to and rotatable with the fan blades or propeller, thereby to increase the centrifugal force of the air stream and consequently impart a higher speed of travel to the air.

A further object is to provide a circulating fan including a casing having an air duct or opening in the top thereof and communicating with the concave face of the air deflecting cone so that, when the propeller is rotated to produce a primary air stream, a certain amount of air above the casing will be drawn downwardly through said duct in contact with the concave face of the cone, thereby producing an induced or secondary air stream which merges into the primary air stream at the periphery of the casing and consequently increases the volume of air output of the fan and the distance of air travel.

A further object is to form the concave face of the cone with a plurality of radiating blades or ribs for directing the secondary stream of air into the primary stream and also to assist in accelerating the movement of the combined air streams.

A further object is to provide a novel form of bearing for the revolving cone and further to provide an air deflecting guard or shield for the air opening or duct, which guard or shield also serves as a handle for lifting and carrying the fan.

A still further object of the invention is generally to improve this class of fans so as to increase their utility, durability and efficiency as well as to reduce the cost of manufacture.

In the accompanying drawings forming a part of this specification and in which similar numerals of reference indicate corresponding parts in all the figures of the drawings:

Figure 1 is a front elevation of an air circulating fan embodying the present invention,

Figure 2 is an enlarged vertical sectional view with a portion of the grill work of the casing omitted for the sake of clearness and showing in full lines the movement of the primary air

stream and in dotted lines the movement of the secondary air stream.

Figure 3 is a perspective view of the deflecting cone, the top plate of the casing and guard or shield detached.

Figure 4 is a side elevation illustrating a modified form of the invention, and

Figure 5 is an enlarged vertical sectional view thereof.

10 The improved air circulator forming the subject-matter of the present invention comprises a supporting frame or casing 5 including a plurality of uprights or posts 6 connected in any suitable manner by vertically spaced reinforcing bands 7, the lower end of the posts being provided with feet 8 adapted to rest on a floor or other suitable support. Welded or otherwise rigidly secured to the outer faces of the reinforcing bands 7 are a series of vertically disposed pickets 9 suitably spaced apart so as to form an ornamental grill for the frame work and also to permit the free flow of air through the grill when the fan is rotated. It will be understood, however, that any other suitable form of grill may be employed and that the invention is not limited to the specific form shown.

Secured to the upper ends of the posts 6 by screws or similar fastening devices 10 is a top or cover plate 11 having a centrally disposed opening or air duct 12 formed therein which communicates with the interior of the frame, as shown. Disposed above the air duct 12 is a shield or guard plate 13, the upper surface of which is preferably tufted at 14 so as to form a seat.

30 Interposed between the shield 13 and the cover plate 11 are spacing members 15 defining an intermediate air passage 16, there being bolts or similar fastening devices extending through the shield, spacing members 15 and cover 11 for detachably securing the shield in position on the cover. The member 13 not only forms a combined air deflecting shield and seat but also forms a handle so that by inserting the fingers beneath the peripheral edge of the shield 13 the fan can be conveniently moved from place to place.

Arranged centrally within the supporting frame is an electric motor 17 having a vertically disposed shaft 18 adapted to detachably receive the hub 19 of a fan or propeller 20, said hub 50 being fastened to the shaft to turn therewith by means of a clamping screw 21. The electric motor 17 may be secured in position in any suitable manner but it is preferred to provide the motor casing with angular suspension brackets 22 which engage corresponding brackets 23 se-

cured to the posts 6, said brackets being detachably secured together by fastening bolts 24.

Disposed above the fan blades or propeller 20 and rotatable therewith is a deflecting cone 25. This deflecting cone 25 may be constructed of metal or molded or otherwise formed from plastic material, said cone having its concave face disposed beneath and spaced from the air duct 12 and its lower end formed with a hollow depending extension 26, the bottom of which is provided with an opening 27 for the reception of the shaft 18. Fitting snugly within the depending extension 26 is a bushing 28 through which the fan shaft 18 passes, there being a clamping screw 29 extending through the member 26 and bushing 28 and bearing against the shaft 18 for keying the cone to the shaft and causing it to rotate therewith. The outer edge of the cone 25 preferably terminates in spaced relation to the posts 6 and welded or otherwise secured to the concave face of the cone 25 are a plurality of downwardly tapered blades or ribs 30 for the purpose of accelerating movement of the air when the fan is in operation. When the cone 25 is formed of plastic material, these ribs 30 will be pressed upwardly from the body of the cone. The outer or wide ends of the blades 30 are preferably curved at 31 and project slightly above the outer edge of said cone so as to direct the air outwardly through the fan grill. The air circulator is provided with a suitable hand operated switch 32 operatively connected with the motor 17 for controlling the flow of current to said motor.

When current is supplied to the motor 17, the propeller 20 will draw air through the grill of the supporting frame and force the air upwardly against the convex surface of the cone 25 to form a primary air stream, said air stream being deflected outwardly by the cone and thence through the upper portion of the grill so as to thoroughly circulate the air in a room or other enclosure. As the fan and cone rotate as a unit, an induced or secondary air stream will be drawn inwardly through the passage 16 and downwardly through the vent 12 against the concave face of the cone 25, the ribs 30 serving to accelerate the movement of the air and direct the air outwardly by centrifugal force where it merges with the primary air stream and is discharged through the upper portion of the grill, as previously stated.

In order to assemble the fan, it is merely necessary to fit the fan hub over the shaft 18 and secure the same by the screw 21, after which the cone 25 with the bushing 28 disposed within the extension 26 is fitted over the upper end of the shaft 18 and keyed thereto by tightening the screw 29. The cover 11 with the guard plate 13 thereon is then fastened to the upper ends of the posts 16 by the fastening devices 10. The parts may be readily disconnected by reversing this operation so as to permit any repairs thereto when necessary.

In Figures 4 and 5 of the drawings, there is illustrated a modified form of the invention in which the electric motor 33 is disposed above the air deflecting cone 34 instead of below the same. In this form of the invention the motor is preferably suspended from the guard or shield 35 by means of bolts 36 surrounded by cushioning sleeves 37, the construction and operation of the device being otherwise similar to that shown in Figures 1 and 2 of the drawings. It will, of course, be understood that the fan motor

may be arranged either above or below the cone without departing from the spirit of the invention.

It will also be understood that the air circulators may be made in different sizes and shapes and constructed of any suitable material without departing from the spirit of the invention.

Having thus described the invention, what is claimed as new is:

10. 1. An air circulator including a casing, a propeller mounted for rotation within the casing, and an air deflecting cone disposed above and spaced vertically from the propeller and mounted for rotation therewith.
15. 2. An air circulator including a frame, a grill secured to and surrounding the frame, a propeller mounted for rotation within the frame, and an inverted cone disposed above and spaced vertically from the propeller and mounted for rotation therewith for deflecting the air stream from the propeller against the convex face of the cone and thence outwardly through said grill.
20. 3. An air circulator including a casing, a propeller mounted for rotation within the casing and including a motor and driving shaft, an inverted cone disposed above and spaced vertically from the propeller and mounted for rotation therewith, said cone being provided with a hollow depending extension fitting over the driving shaft, a bushing fitting within the hollow extension, and a fastening device extending through the hollow extension and bushing and engaging the driving shaft, the convex face of the cone serving to deflect the air stream from the propeller outwardly through said casing.
25. 4. An air circulator including a casing having an air duct in the top thereof, a shield fitted over and spaced from the air duct, a propeller mounted for rotation within the casing, a cone disposed above and mounted for rotation with the propeller for directing a primary air stream from said propeller outwardly through the casing, the rotation of said cone serving to set up an induced secondary air stream through the air duct and deflect the same outwardly through the casing.
30. 5. An air circulator including a casing having an air duct, a propeller mounted for rotation within the casing for producing a primary air stream, a cone disposed above and mounted for rotation with the propeller for deflecting the primary air stream outwardly through the casing, and radiating blades secured to the concave side of the cone for producing an induced secondary air stream through the air duct merging with the primary air stream adjacent the inner wall of said casing.
35. 6. An air circulator including a casing having a top provided with a centrally disposed air duct, a shield secured to and spaced from the top of the casing at said air duct and constituting a combined seat and hand grip, a propeller mounted for rotation within the casing for producing a primary air stream, a cone disposed above and mounted for rotation with the propeller for deflecting the primary air stream outwardly through the casing near the top thereof, and radiating blades secured to the concave side of the cone for setting up a secondary air stream through said air duct and directing the secondary air stream outwardly for emergence with the primary air stream.
40. 7. An air circulator comprising a casing including spaced uprights, a grill surrounding the casing and secured to said uprights, a cover for the casing secured to the uprights and provided with

a centrally disposed air duct, an electric motor arranged within the casing and including a driving shaft, a propeller having a hub detachably secured to the shaft, a cone disposed beneath the air duct and having its lower end provided with a hollow depending extension fitting over the driving shaft and resting on the propeller hub, a bushing fitted with said extension, means extending through the bushing and engaging the driving shaft for keying the cone thereto, and a plurality of radially disposed upstanding blades secured to the concave side of the cone at the periphery thereof and having their inner ends spaced from the hollow extension.

8. A portable air circulator comprising a casing including a top having an air vent formed therein, an electric motor including an upright drive shaft disposed within the casing, a propeller keyed to

5 the driving shaft, a shield disposed above the air duct and spaced from the top of the casing to form a passage, spacing members interposed between the shield and top of the casing, fastening devices extending through said spacing members and engaging the top of said casing, the rim of said shield forming a carrier handle, a cone disposed below the air duct and provided with a depressed hollow extension fitting over the adjacent end of the driving shaft and secured thereto for rotation therewith, the outer edge of said cone being spaced from the inner wall of the casing and the concave side thereof provided with spaced radiating blades having their outer ends curved and their rear ends tapered toward the hollow extension and terminating short thereof.
